Res. 2349

Edward F. Kelly of Chicago, Ill.

Letter Patent 1,223,349. Dated July 27, 1917.

Design for the Examination of

affixed to the side of a top, the side being curved to fit the

shape of the top, very concave.

It is known that Edward F. Kelly, of the
City of Chicago, in the State of Illinois, have produced a new and
original design for the examination and marking of clipping
tops, and it is hereby declared that the following description and
specifications, in so far as to limit the top being contemplated in the
present invention, is a top, with a flat top, in the centre of the top
or upper surface, there being a small circular part to be marked or painted on
the top, with the same being of a different color from the top, and in a
circular line, and on the star and the outer edge of the top is painted
or printed or stamped the following words: "The Race Top is as shown in
the drawing, directed upward."
